CLAIM

The ornamental design for a tool bag, as shown and described.

DESCRIPTION

FIG. 1 is a top perspective view of a tool bag, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a split state diagram; and,

FIG. 10 is an enlarged detail view of area 10 in FIG. 1. The dash-dash broken lines in the drawings depict portions of the tool bag that form no part of the claimed design. The long dash-short dash broken lines depict enlargement boundary lines that form no part of the claimed design.

1 Claim, 10 Drawing Sheets(56)
